UNITED STATES PATENT OFFICE

MAURUS C. RECK, OF ROCHESTER, NEW YORK, ASSIGNOR TO STERLING RANGE AND FURNACE CORPORATION, OF ROCHESTER, NEW YORK, A CORPORATION OF NEW YORK

WATER-HEATING APPARATUS

Application filed May 1, 1929. Serial No. 359,656.

- The present invention relates to water heating apparatus and more particularly to the type employed in connection with gas stoves or ranges where different fuels are used, such 5 for example, as coal and gas. One object of the invention is to provide improved apparatus of this class which is efficient in service, comparatively simple in construction and convenient to operate.
- 10 A further object of the invention is to provide improved means by which to effect a reduction in the temperature of the products of combustion after leaving the combustion chamber and before reaching the discharge 15 pipe leading from the stove whereby to avoid the danger of fire due to excessive temperature in the pipes.
- A further object of the invention is to provide an improved heating arrangement including means for controlling the products 20 of combustion designed to insure economy in the use of the fuel with an increase in the heating capacity.
- To these and other ends the invention re- 25 sides in certain improvements and combinations of parts, all as will be hereinafter more fully described, the novel features being pointed out in the claims at the end of the specification.
- 30 In the drawings:
- Fig. 1 is a side elevation of the upper portion of a stove embodying the invention;
- Fig. 2 is a fragmentary part sectional elevation illustrating the arrangement of the 35 heating coils and associated parts;
- Fig. 3 is a transverse sectional elevation taken substantially on line 3^a—3^a of Fig. 2;
- Fig. 4 is a part sectional plan taken sub- 40 substantially on line 4^a—4^a of Fig. 3.
- Fig. 5 is a fragmentary sectional plan taken on line 5^a—5^a of Fig. 2; and
- Fig. 6 is a sectional plan taken on line 6^a—6^a on Fig. 2.

Similar reference numerals throughout the 45 several views indicate the same parts.

The present construction comprises generally a stove or range embodying a heating arrangement having separate combustion chambers, the heat from either one of which may 50 be utilized to heat the water in the circulating

system, or if preferred both may be used at the same time to afford a more rapid increase in the temperature of the water. One of the important features of the invention embodies the improved means for insuring the passage 55 of the products of combustion into more direct relationship with the coils in the gas heated chamber, along with means for retarding the passage of the gas from the chamber whereby to economize in the use of fuel 60 while maintaining the efficiency of the apparatus and reducing the time required to heat the water to a given degree of temperature.

The apparatus further embodies the combination of a cooling space or spaces in the form of one or more chambers between the outlet pipe for the gas and the combustion chamber along with an improved arrangement for delivering cold air to said chambers for reducing the temperature of the products 70 of combustion therein in order to avoid excessive temperatures within the outlet pipe and the consequent danger from fire likely to result therefrom.

In the embodiment of the invention illustrated in the drawings 10 designates the top of the stove, 11 and 12 the front and rear walls respectively, and 13 one of the side walls to which is hinged a door 14. The side wall 13 is suitably connected with the front and rear walls and also with a vertical main side wall comprising the upper and lower sections 15 and 16 respectively as best shown in Fig. 3. The oven compartments are not shown, but one of the side walls therefor is indicated at 17, and the smoke pipe for carrying off the products of combustion is shown at 18, Fig. 3.

The fire box for burning coal or the like is designated at 19 and is provided with grate sections 20 and fire brick walls 21 at the front, back and along one side which are preferably carried by a frame 22 supported by the walls 16 and 17 as shown in Fig. 3. The outer side of the fire box is closed by a hollow casting forming a water compartment, the inner wall of the casting being indicated at 23 and the outer wall at 24. A horizontal partition 25 separates the compartment into lower and upper chambers 26 and 27 which are connected with inlet and 100

outlet pipes 28 and 29 respectively. These pipes are connected with the water supply or boiler (not shown). One or more openings 30 are formed in the wall of the partition to permit the water to circulate from the lower to the upper chamber. The casting is suitably supported by the upper and lower sections 15 and 16 of the left side wall of the stove as viewed in Fig. 3.

For the purpose of heating the water when the fire box is not in use a gas burning chamber 31 is employed adjacent the outer wall 24 of the casting. Arranged within this chamber are a plurality of water conducting coils 32 each having an inlet portion 33 connected with the lower chamber 26 and an outlet portion 34 connected with the upper chamber 27, it being understood that the water circulates simultaneously through the coils, passing from the lower chamber to the coils and discharging therefrom into the upper chamber. A cone-shaped member 35 is placed within each coil with its smaller end at the bottom of the coil, the purpose of these members being to spread and retard the products of combustion when passing through the coils whereby to increase the efficiency of the heater. The cone-shaped members being larger at their upper than at their lower ends tend to delay or choke the passage of the burning gas within the coils and to direct it against the surfaces thereof whereby to more effectively heat the same.

Beneath the heating chamber 31 is located a longitudinally extending gas burner 36 which is supported at its rear end by a lug 37 extending through an opening 38 in the rear wall 12 of the chamber which forms a support for the lug. The burner is supported adjacent its front end by lugs 39 on the wall sections 13 and 16 respectively as shown in Fig. 3. Connected with the burner is a short mixing pipe 40 of the usual construction, into the lower end of which projects the discharge nipple of a valve 41 connected with a suitable manifold or supply pipe 42, Fig. 2.

Beneath the burner is a bottom plate 43 the rear end of which is slotted at 44 to receive the mixing pipe 40, said end being supported by a collar 45 on the mixing pipe. The front end of the plate 43 rests on an inwardly projecting flange-like portion 46 of a door or closure 47 for an opening in the front wall 11 opposite the front end of the burner 36. The plate 43 is preferably secured to said flange-like portion by a bolt 48. The closure 47 is provided with two inwardly projecting lugs 49, Figs. 2 and 5, which rest upon lugs or abutments 50 on the walls 13 and 16 between which the burner is disposed. An additional lug 51 projects inwardly from the closure 47 and engages the inner face of the wall 13 to steady and prevent lateral shifting of the closure. A pivoted latch 52 is provided for holding the closure

in position as indicated in Fig. 2. The closure has a flange 53 at right angles to its face which abuts the end of the lower portion of the side wall 13. The plate is provided with a plurality of openings 54 for the admission of secondary air to the burner chamber. Furthermore, the sides of the plate are slightly spaced from the walls 13 and 16, Fig. 3 to afford openings 55 and 56 for admitting an additional supply of secondary air to the burner chamber. The plate 43 is in the form of a shallow pan, designed to catch the drippings from the coils 32, due to condensation, which will be quickly evaporated by the heat from the burner. The side walls of the pan are formed by turning up the peripheral edge portion of the plate, as at 43^a and providing upstanding portions 44^a surrounding the openings 54.

The closure 47 and the pan attached thereto can be readily withdrawn as a unit so that the burner and mixing pipe 40, constituting another unit, may be quickly detached by a longitudinal movement through the opening protected by the closure, after the rear end of the burner has been lifted sufficiently to permit the lower end of the mixing pipe to clear the discharge nipple on the valve 41. By suspending the burner in the manner described it will be seen that it can be detached and cleaned whenever necessary and reinserted without the use of tools for disconnecting any parts of the burner or the supporting means therefor.

Interposed between the rear coil 32 and the wall 12 is a channel-shaped member 57 which is closed at its top and bottom, but which is preferably open at its ends, said ends being slightly spaced from the walls 13 and 24, the latter being the outer wall of the casting through which the water circulates. An insulating air space 58 is thus provided between the rear coil 32 and the wall 12 for conserving the heat and also for protecting the wall 12 from the high temperatures of the combustion chamber. A second channel-shaped member 59 is interposed between the first coil 32 and the wall 11 for the same purpose with an insulating air space 60 between said parts. Said channel-shaped members also constitute means for causing the heated gas at the ends of the chamber 31 to be directed upwardly into contact with the end coils 32 whereby to insure greater efficiency in the heating capacity of the chamber. The channel-shaped members are held in position by one or more screws 61 serving to clamp the members in the position shown. The channels 57 and 59 can be readily removed through the door opening and new channels substituted when desired. The channel 57 has an inwardly projecting shelf-like portion 62 with its inner edge shouldered to receive one end of a cover plate 63 the opposite end of which is formed for support by the upper

portion of the channel 59 as shown in Fig. 2. A pivoted latch 64 is carried by said shelf-like portion for holding the cover plate in position to close the chamber 31, said plate being removable through the door openings 5 when the latch is released. The cover is curved upwardly at its inner edge and is shouldered as indicated in Fig. 3 to engage the bottom edge of the wall 15 and the outer 10 face thereof as well. The cover is disposed directly over the coils 32 to check the flow of gas from the heating chamber. The cover, at a point over the left hand coil 32 Fig. 2, has an opening 63^a for the escape of the products 15 of combustion and is also cut away at 64^a for the same purpose. A more rapid escape of the gas at this point is desirable for the reason that it accumulates faster at the end of the chamber than elsewhere due 20 to the proximity of the inlet pipe 40 to the discharge ports at the left hand end of the burner.

The side wall 15 above the heating chamber 31 is provided with an outlet passage 65 leading to a cooling chamber or flue 66 above the fire box 19 which is in direct communication with the outlet pipe 18. When relying entirely on the burning of fuel in the fire box 19 to both heat the stove and the water passage 65 may be closed by a damper 67 as shown by the dotted line positioned in Fig. 3. The damper is provided with trunnion like portions 68 and 69, the latter of which is preferably made detachable, said portions 35 being journaled in suitable bearings 70 projecting from the wall 15 as shown in Fig. 3. The trunnion 69 is extended through the wall 11 and carries a handle or operating portion 71 for swinging the damper to and from 40 closed position. The damper may be locked in open position by a pivoted latch 72, which forms no part of the present invention. The trunnion 68 is extended through the left hand wall 12 of the heating chamber 31 and is provided 45 with a crank arm 73 to which is connected a rod 74, the lower end of which connects with the operating portion 75 of the gas inlet valve indicated generally at 41 in Fig. 2. With this arrangement for moving the 50 damper to and from closed position the valve will be automatically closed and opened to control the supply of gas to the burner.

The vertical portion of the door 14 is spaced from the plane of the wall 13 and is provided with inwardly projecting lugs 76 for supporting a vertically disposed plate 77 relatively close to the heating coils 32. The lower end of the plate 77 is substantially coincident with the lower wall section 13 as shown 55 in Fig. 3. The upper end of the said plate is provided with an inturned flange 78 which overlies the cover plate 63, thus forming a choke chamber 79 for the products of combustion which serves to delay the passage of 60 the gas on its way to the cooling chambers

80 and 66 and the outlet pipe 18. The plate 77 is provided with a plurality of V-shaped ribs 81, only one of which is shown. These ribs are disposed opposite the openings between the coils 32 whereby to afford an opening of more uniform proportions for the passage of the gas discharging into the choke chamber 79. 70

By spacing the plate 77 from the door a cold air passage 82 is provided which is open 75 at its lower end for substantially the full length of the door. The passage 82 terminates at its upper end in a somewhat restricted outlet 83 formed by spacing the flange 78 but slightly below the lower edge of the upper wall section 13. The cold air discharging through the outlet 83 enters the cooling chamber 80 in which the damper operates and into which a considerable portion of the heated gas is discharged from the choke 85 chamber 79. A portion of the cold air will pass between the upper edge of the damper and the wall 13 and the remaining portion beneath the damper. By breaking up the cold air current in this manner within the chamber 80 it will become more thoroughly 90 mixed with the products of combustion discharging from the choke chamber 79. The cold air admitted to the chamber 80 continues to mix with the products of combustion while 95 passing through the cooling chamber 66 to the pipe 18 and by the time the mixture reaches the pipe its temperature is reduced sufficiently to overcome any danger from fire which might result from excessive temperatures within that portion of the pipe passing through the walls of the room. The damper when in open position as shown in Fig. 3 100 functions to effect a more complete mixing of the gas and cold air by the turbulence produced within the chamber 80, due to the arrest by the damper of the air and gas currents flowing into the chamber. By restricting the size of the cold air passage 83 the 105 velocity of the air will be somewhat increased when entering the chamber 80 whereby a more complete mixing of the gas and air will be afforded.

Since the top of the heating chamber 31 is substantially closed except for a relatively 110 narrow outlet passage at one side thereof, extending between the closure 63 and plate 77 and since the chamber 79 serves as a choke passage, the products of combustion will be retained within the chamber 31 for a maximum period and consequently greater efficiency is insured with a minimum consumption of the fuel. The cooling of the products of combustion in the manner described is highly advantageous for the reasons stated. Furthermore the passing of the relatively 115 cold air or that which is at room temperature upwardly through the door chamber 82 serves the double purpose of cooling the products of combustion and of protecting 120 125 130

the door from the relatively high temperatures in the heating chamber. The choking of the burning gas within the coils by means of the cone-shaped members 35 is obviously 5 advantageous since it results in forcing the gas into direct contact with the coils. It will be understood as stated above that when it is desired to use only the fire box 19 as a heating chamber the damper 67 will be closed. However for a more rapid heating of the water 10 both combustion chambers may be used at the same time.

I claim as my invention:

1. In a water heating apparatus, the combination of a heating chamber, fuel burning means at the bottom thereof, water circulating means within said chamber, a cooling chamber above the heating chamber, separating means between said chambers designed to restrict the flow of the products of combustion to the cooling chamber and means at one side of the heating chamber forming a vertical passage for the upward flow of cold air to the cooling chamber.

2. In a water heating apparatus, the combination of a heating chamber, fuel burning means at the bottom thereof, water circulating means within said chamber, a cooling chamber above the heating chamber, separating means between said chambers designed to restrict the flow of the products of combustion to the cooling chamber, means at one side of the heating chamber forming a passage for the delivery of cold air to the 20 cooling chamber and means extending within said cooling chamber serving to increase the turbulence of the air and gas discharging thereto whereby to more intimately mix the same.

3. In a water heating apparatus, the combination of a heating chamber, fuel burning means at the bottom thereof, water circulating means disposed within the chamber, a cooling chamber overlying the heating chamber, means interposed between said chambers affording a restricted outlet for the discharge 40 of the products of combustion to the cooling chamber, one of the side walls of the heating chamber being extended above the top of the 50 chamber and having a flange-like portion projecting into the cooling chamber, and a vertically disposed plate spaced from said side wall and cooperating therewith to form a cold air passage leading upwardly and discharging into the cooling chamber above said flange-like portion.

4. In a water heating apparatus, the combination of a heating chamber, fuel burning means at the bottom thereof, water circulating means within said chamber, a cooling chamber above the heating chamber, separating means between said chambers designed to limit the flow of the products of combustion to the cooling chamber, means forming 60 a passage for the delivery of the cold air to

said cooling chamber, and a second cooling chamber separated from the first by a vertical side wall, said wall having an opening for the passage of the air and gas to the said second cooling chamber.

5. In a water heating apparatus, the combination of a heating chamber, fuel burning means at the bottom thereof, water circulating means within said chamber, means substantially closing the upper end of said chamber designed to afford a limited outlet for the discharge of the products of combustion therefrom, separate cooling chambers above 70 said heating chamber having a communicating passage therebetween, one of said chambers communicating with the heating chamber, means for opening and closing said passage and means forming a supply passage for the delivery of cold air to the cooling chamber communicating with the heating chamber.

6. In a water heating apparatus, the combination of a heating chamber, fuel burning means at the bottom thereof, water circulating means within said chamber, a cooling chamber above said heating chamber, a choke chamber between said cooling and heating chambers for checking the flow of the heated gas discharging from the heating chamber and means forming a vertically disposed cold air passage arranged to discharge at its upper end into said cooling chamber.

7. In a water heating apparatus, the combination of a heating chamber, fuel burning means at the bottom thereof, water circulating means within said chamber, a cooling chamber above said heating chamber, means forming a transversely extending choke chamber between the first mentioned chambers, said choke chamber having an inlet at one end and an outlet at the other discharging into the cooling chamber and means forming a cold air passage leading to the cooling chamber.

8. In a water heating apparatus, the combination of a heating chamber, fuel burning means at the bottom thereof, water circulating means within the chamber, a plate extending across the top of said chamber having one edge spaced from one of the side walls of the chamber to form a relatively narrow passage for the escape of the products of combustion, a cooling chamber communicating with said heating chamber through said passage and a plate member spaced from said side wall and cooperating therewith to form a vertically disposed cold air passage open at its lower end and discharging at its upper end into said cooling chamber to cool the products of combustion discharging thereto from the heating chamber.

9. In a water heating apparatus, the combination of a heating chamber, fuel burning means at the bottom thereof, water circulating means within said chamber, a cooling

- chamber above said heating chamber, a wall interposed between said chambers having a restricted outlet for the escape of the gas to the cooling chamber, a vertically disposed plate spaced from one of the side walls of the heating chamber to form a cold air passage communicating at its upper end with the lower portion of said cooling chamber, said cooling chamber having an outlet at one side thereof and a plate extending longitudinally within said cooling chamber between the top and bottom thereof and in spaced relation to the side walls of the chamber and serving to direct a portion of the inflowing air to the upper part of said chamber. 5
10. In a water heating apparatus, the combination of a cooling chamber, a heating chamber below the cooling chamber separated from the latter by a wall constructed to afford a relatively narrow outlet adjacent one of the side walls of the heating chamber for the escape of the products of combustion to the cooling chamber, water circulating means within the heating chamber, a gas burner at the bottom of the heating chamber, and a door at one side of the heating chamber forming a support for said side wall, the latter being spaced from the door and cooperating therewith to form a cold air passage 20 open at its lower end and communicating at its upper end with said cooling chamber. 25
11. In a water heating apparatus, the combination of a heating chamber having side and end walls, a plurality of water circulating coils within the chamber, plate members on said end walls cooperating with portions thereof to form insulating air spaces and also serving to direct the products of combustion inwardly from the lower end portions of the 30 heating chamber, a cooling chamber overlying the heating chamber, a wall separating said chambers and having its ends resting on and supported by said plate members, said wall being constructed to limit the flow of the 35 products of combustion from the heating to the cooling chamber, and a gas burner at the bottom of the heating chamber. 40
12. In a water heating apparatus, the combination of a heating chamber comprising side and end walls, plate members arranged adjacent said end walls to form insulating air spaces for the protection thereof, a door at one side of the heating chamber, a wall overlying said heating chamber and supported by said plate 45 members, said wall affording a relatively narrow outlet for the escape of the products of combustion from said chamber and being removable through the door opening, a cooling chamber above the heating chamber communicating with said outlet, a gas burner at the bottom of said heating chamber, and water circulating means within the heating chamber. 50
13. In a water heating apparatus, the combination of a heating chamber comprising 55
- side walls and an upper closing wall constructed to afford a relatively narrow passage adjacent one of the side walls for the escape of the products of combustion, the opposite side wall comprising a water compartment, water 60 circulating coils within said chamber directly below said upper wall, said coils being in communication with said water compartment, a gas burner at the bottom of said chamber, a cooling chamber above said heating chamber, and a choke passage between said chambers having one end communicating with said relatively narrow passage and the other end provided with an outlet passage discharging to the cooling chamber. 65
14. In a water heating apparatus, the combination of a heating chamber having a relatively narrow outlet in its top wall adjacent one of its side walls, its opposite side wall comprising a water circulating compartment, 70 a plurality of vertically disposed water circulating coils within said chamber having their end portions connected with said compartment, a cone-shaped member extending vertically within each coil with its smaller 75 end adjacent the bottom of the coil, a gas burner at the bottom of said heating chamber, a cooling chamber above said heating chamber and a plate member projecting inwardly from the side wall opposite said compartment at a point directly above said outlet whereby to deflect the products of combustion passing from the heating to the cooling chamber. 80
15. In a combined coal and gas water heater, the combination with a water compartment forming one wall of a fire box, a gas heated chamber located adjacent the fire box, a plurality of water circulating coils within the gas heated chamber communicating with said water compartment, of a cooling chamber above the heating chamber separated therefrom by a wall affording a restricted passage for the products of combustion to the cooling chamber and a door spaced from one of the side walls of the heating chamber arranged to support the latter and cooperating therewith to form a vertically disposed cold air passage open at its lower end and communicating at its upper end with said cooling chamber. 90
16. In a combined coal and gas water heater, the combination with a water compartment forming one wall of a fire box, a gas heated chamber located adjacent the fire box, a plurality of water circulating coils within the gas heated chamber communicating with said water compartment, of a cooling chamber above the heating chamber separated therefrom by a wall affording a restricted passage for the products of combustion to the cooling chamber, a member spaced from one of the side walls of the heating chamber forming a vertically disposed cold air passage open at its lower end and communicating at 100
- 110
- 120
- 125
- 130

its upper end with said cooling chamber, an adjustable member extending within the cooling chamber forming means for increasing the turbulence of the air and gas flowing thereto, and a second cooling chamber adjacent one of the side walls of the first mentioned cooling chamber, said wall having an opening for the escape of the mixture of air and gas to the second cooling chamber, said 10 adjustable member being movable to close said opening when the fire box is used to heat the water.

17. In apparatus of the class described, a heating chamber, a burner compartment at the bottom of said chamber, a burner extending longitudinally within said compartment, a closure for one end of the compartment, a gas supply pipe connected with the burner, and a bottom plate for the burner compartment having one end supported by said pipe and the other by said closure, the closure and bottom plate being removable as a unit.
